UNITED STATES PATENT OFFICE.

JULIAN H. PITKIN, OF RAVENSWOOD, AND JULIUS S. LANE, OF OAK PARK, ILLINOIS.

COMPOUND LOCOMOTIVE OR OTHER COMPOUND ENGINE.

SPECIFICATION forming part of Letters Patent No. 430,969, dated June 24, 1890.

Application filed December 12, 1889. Serial No. 333,479. (No model.)

To all whom it may concern:

Be it known that we, JULIAN H. PITKIN, of Ravenswood, and JULIUS S. LANE, of Oak Park, in the county of Cook and State of Illinois, have invented certain Improvements in Compound Locomotives or other Compound Engines, of which the following is a specification.

Our invention relates to what are known as "compound locomotives," in which the steam is first used at high pressure in small cylinders and then exhausted into large cylinders, in which it is again used expansively at correspondingly low pressure.

The aim of the invention is principally to provide simple and convenient means for developing the abnormal amount of power required in starting the train and until it is under full headway; and to this end the improvement consists in a novel arrangement of throttle-valves and their operating devices by which the admission of steam to the smaller cylinders may be controlled, as usual, or steam admitted at will directly from the boiler into the large cylinders, as will hereinafter more fully appear.

Under our organization the movement of one lever operates two throttles and admits steam from the boiler to both the high and low pressure cylinders to start the engine. The independent operation of a second lever then closes one throttle and cuts off the high-pressure steam from the low-pressure cylinders. To stop the engine it is only necessary to close the main throttle by moving the first-named lever, which at the same time establishes its connection with the secondary throttle, so that it may again open both throttles. It is this combination of the two throttles with mechanism by which they are operated jointly and separately that forms the essence of our invention.

In the accompanying drawings, Figure 1 is a side elevation of a locomotive having our improvement incorporated therein, the cylinders, their valve mechanism, and other parts being shown in vertical section. Fig. 2 is a vertical cross-section of the same, taken on one side through the larger cylinder on the line $x x$ and on the opposite side through the

smaller cylinder on the line $y y$. Fig. 3 is a side elevation of the lever-connections employed for operating the throttles. Fig. 4 is a front elevation of the same. Fig. 5 is a sectional view of a detail.

In all its essential particulars, and with the exception of the branch pipe for admitting steam directly to the large cylinders and the throttle arrangements hereinafter described, the locomotive shown in the drawings is of ordinary construction. On each side there is a forward cylinder A, containing an ordinary piston and provided with the usual steam-chest a and slide-valve a' , by which the steam is delivered to and from the opposite end of the cylinder. Directly behind the cylinder A there is a second and larger cylinder B, also provided with a steam-chest b and with an ordinary slide-valve b' for the admission and delivery of the steam. The pistons of the two cylinders are connected, as usual, by an intermediate rod c , which is in turn connected through the ordinary devices with the driving-wheels. The slide-valves of the two cylinders are connected by intermediate rods d , operated through the ordinary link and eccentric connections from the axle of the forward driver. Live steam is delivered through pipe D from the dome of the boiler into the chest of the forward and smaller cylinder A. A pipe E leads from the exhaust-port of the forward and smaller cylinder to the steam-chest of the larger cylinder.

The foregoing parts are all of ordinary construction and arrangement, and in the normal condition of affairs operate as usual, the steam being delivered through the pipe D into the chest of the smaller cylinder, thence to said cylinder, thence into the chest of the larger cylinder, and finally into the larger cylinder and thence to the exhaust.

In order that the live steam may be admitted directly to the larger cylinder, we provide the steam-supply pipe D near its forward end with branches D', leading, as shown, directly into the chests of the cylinders B. At the junction of these branches D' with the main pipe D we provide a throttle-valve F, of any approved construction, by which the flow of steam through the branches may be con-

trolled without affecting the flow to the smaller cylinders.

- At one end the main pipe D is provided with the usual throttle G, controlling the admission of steam thereto. When the throttle G is closed, steam is shut off from all of the cylinders. When the throttle G is open and throttle F closed, steam will pass directly to the forward cylinders only and thence to the rear cylinders. When, however, the throttles G and F are both open, live steam will pass directly to the chest of the forward cylinder and also directly to the chest of the rear or larger cylinder. The steam thus admitted to the chest of the larger cylinder will be delivered to the cylinder by the ordinary action of the valve and will operate at high-pressure on the piston, thus developing an abnormal amount of power and enabling the engine to readily start the train. It is to be observed that during this operation the forward cylinder receives live steam not only through its valve to one side of the piston, but at the same time through pipe E from the chest of the larger cylinder to the opposite side of the piston, and this during the movement of the piston in both directions. Thus it will be seen that the forward piston is subjected to counteracting or neutralizing pressures on opposite sides during the time that high-pressure steam is used in the larger cylinders, so that for the time being the forward cylinders and pistons are practically inactive or ineffective. The instant that the throttle F is closed, so that steam can no longer pass directly to the larger cylinder or through the pipe E to the smaller cylinder, the engine resumes its original action as a compound engine. For the purpose of enabling the engineer to readily open both throttles, as required, in starting the engine and thereafter close the forward throttle independently, we provide the following arrangement: The main throttle G is connected with a hand-lever H either by means of a rod h, lever h', and link h², as shown, or by any equivalent connections which will impart a positive motion from the lever to the valve. This lever H is provided with an ordinary locking-dog h⁴, operated by a thumb-latch h⁵, and engaging a toothed locking-plate h⁶, by which the main throttle may be held in any required position. By the side of the main lever H, and preferably on the same axis, we mount a second hand-lever I, provided with a locking-dog i, operated by the usual thumb-latch and arranged to engage a notched arm h⁷ on the main lever H. This admits of the two levers being locked together and operated as one, or of the secondary lever being independently operated. From the secondary lever we extend devices of any suitable character for operating the secondary throttle F. This connection may consist of a rod i', connected by an elbow-lever i² to the throttle, as shown in Fig. 5, or any other equivalent mechanical

action. In order, however, to reduce the labor of operating the parts, we prefer, as shown in Figs. 1 and 2, to connect the spindle of the throttle F to a piston f in the cylinder f', provided with a rocking valve f², through which steam may be admitted above or below the piston at will to open or close the throttle. This steam-controlling valve is connected by rod i' with the lever I. In the normal condition of the parts with the engine at rest the lever H stands in its forward position with the lever I thrown forward and locked thereto. If now the lever H is moved to the rear, it carries with it the secondary lever, the two moving as one and opening both throttles, so that live steam is admitted from the boiler directly to the larger and also to both ends of the smaller cylinders. The lever II may be adjusted to control the rate of steam-delivery at will. When the train has acquired the proper momentum, the secondary lever I is unlocked from the main lever and thrown forward, thereby causing the closure of the throttle F, thus shutting off the direct delivery of steam to the larger cylinders without affecting its delivery to the others.

To stop the engine, it is only necessary to throw forward the larger lever and close the main throttle G. When this is done, the locking device or catch automatically secures the secondary lever to the main lever in such position that the backward motion of the main lever will again open both throttles, as in the first instance.

The essence of our invention resides, it will be perceived, in connection with the two throttles in such manner that they may be operated jointly or independently at will, and it is to be understood that our invention includes any form of connection the mechanical equivalent of that herein shown.

It will of course be understood that the two sides of our locomotive are constructed in duplicate, as usual, so that the description of one side applies equally well to the other, and also that our improvement, although intended more especially for locomotive engines, is also applicable to other compound engines, such as hoisting-engines, marine engines, &c.

Having thus described our invention, what we claim is—

1. In a compound engine, and in combination with the usual communicating cylinders and their valves, a throttle controlling the steam-delivery to both cylinders, a throttle controlling the delivery of steam to the larger cylinder only, and connecting devices between said throttles, substantially as shown, for operating them independently or jointly at will.
2. In a compound engine, the main steam-pipe, its throttle, and the throttle-operating lever controlling the steam-delivery to the high-pressure cylinder, in combination with the branch pipe for delivering high-pressure steam

to the low-pressure cylinder, the throttle of the branch pipe, its operating-lever, and devices whereby said levers may be connected together or disconnected at will.

5 3. In a compound engine, the main throttle and lever controlling the delivery of steam to both the high and the low pressure cylinders, and a locking device to hold the lever, as usual, in combination with the secondary throttle and lever for admitting high-pressure steam directly to the low-pressure cylinder, and the toothed bar and catch connecting said levers.

4. In a compound engine, the steam-pipe leading from the boiler to the high-pressure cylinders, and the main throttle-valve and its lever controlling said pipe, in combination

with the branch pipe leading to the low-pressure cylinders, the throttle in the branch pipe, the piston f , and the cylinder f' to operate the second throttle, the steam-pipe leading from the boiler to cylinder f , the valve f^2 , the operating rod and lever, and the catch or locking device connecting said lever with the main throttle-lever.

25 In testimony whereof we hereunto set our hands this 31st day of October, 1889, in the presence of two attesting witnesses.

JULIAN H. PITKIN.
